RADIANT HEATER SUSPENSION PANEL FOR THE MODESTY PANEL OF A DESK

Louis J. Reynolds, Santa Fe, N. Mex., assignor to Aztec Electric Heat (a division of Reynolds Electrical & Engineering Co., Inc.), Santa Fe, N. Mex.

Filed Dec. 14, 1964, Ser. No. 83,307

Term of patent 14 years

(Cl. D81—1)

FIG. 1

FIG. 2

FIG. 3

FIG. 4

FIG. 1 is a front perspective of the radiant heater showing my new design;

FIG. 2, a rear elevational thereof;

FIG. 3, an end or vertical elevational thereof; and

FIG. 4, a top elevational thereof.
The essential portion of my design resides in the off-center position of the handles upon the radiant heater face of the panel as shown.

I claim:

The ornamental design for a radiant heater suspension panel for the modesty panel of a desk, as shown and described.
